UNITED STATES PATENT OFFICE.

REUBEN RODEN, OF GRAND RAPIDS, MICHIGAN, ASSIGNOR TO HATTIE W. RODEN, OF GRAND RAPIDS, MICHIGAN.

DESIGN FOR A TIRE.

Application filed May 12, 1924. Serial No. 9,564. Term of patent 3½ years.

To all whom it may concern:

Be it known that I, REUBEN RODEN, a citizen of the United States, residing at Grand Rapids, in the county of Kent and State of Michigan, have invented a new, original, and ornamental Design for Tire, of which the following is a specification, reference being had to the accompanying drawing, forming part thereof.

The figure is a perspective view of a tire, showing my new design.

I claim:

The ornamental design for a tire as shown.
REUBEN RODEN.
